UNITED STATES PATENT OFFICE.

ORSON W. BENNETT, OF WASHINGTON, DISTRICT OF COLUMBIA.

PRESSURE-REGULATOR FOR GAS-BURNERS.

SPECIFICATION forming part of Letters Patent No. 392,489, dated November 6, 1888.

Application filed March 3, 1888. Serial No. 266,044. (No model.)

To all whom it may concern:

Be it known that I, ORSON W. BENNETT, a citizen of the United States, residing at Washington, District of Columbia, have invented 5 certain new and useful Improvements in Pressure-Regulators for Gas-Burners; and I do hereby declare the following to be a full, clear, and exact description of the invention, such as will enable others skilled in the art to which it 10 appertains to make and use the same.

My invention relates to improvements in gas-pressure regulators especially applicable to single or separate burners in which two or more opposing currents tend to neutralize the 15 excess of pressure required to maintain a proper city service.

Two or more passages in opposition to each other leading to a single passage cause the parts of the divided current to impinge against 20 each other, and the flow is thus retarded in proportion to the pressure or force of the branches of the current. An approximately constant pressure is thus obtained and maintained at and beyond the junction of the opposing branches, notwithstanding the fact that 25 the pressure from behind may vary to a considerable extent.

The invention consists in an automatic check or regulating plug for gas-burners provided 30 with axial passage at one end, an annular reduction or passages along the periphery at the other end, and centripetal passages opposite each other leading from the peripheral passages to the axial passage.

35 In the drawings forming a part of this specification, Figures 1 and 2 are sections of a gas-burner complete with my invention applied thereto. Fig. 3 is a check in elevation showing passages along the sides leading to the 40 centripetal passages. Figs. 4 and 5 are sections of different forms of check to be inserted within the pillar.

A is the pillar, and B is the tip of an ordinary gas-burner, which together constitute a 45 complete burner.

C is my improved automatic check-plug having an annularly-reduced end or side channels, c c, the centripetal passages c' c', and the axial passage c''. This check-plug is slightly conical at one end and of a size to be inserted into and removed from the interior of the pillar.

It may be made integral with or be attached to the tip, as shown in Fig. 1 of the drawings,

thus constituting a self-regulating tip, or, as shown in the other figures of the drawings, as 55 a separate piece adapted to be inserted through the lower end of the pillar and held in place by friction. This check may become a distinct article of manufacture to be sold for application and use with the ordinary burner- 60 pillar.

It should be observed that as the check part of the burner regulates the amount of gas to be consumed, relatively large tips should be used with it. A greater amount of light is obtained with a given amount of gas in this way than would otherwise be the case, because in a city service there must be a pressure in excess of the best conditions in order that a large number of consumers may be fully supplied. This check-plug being detachable, may be removed from the pillar for the purpose of cleaning, for the purpose of being replaced by another of different capacity, or to convert the whole to the ordinary form of burner as occasion may require or judgment dictate. 75

In practice I make the lower end of the check only slightly smaller than the body part; but that there may be a full supply of gas to the centripetal passages I make an annular 8c groove around the plug leading directly to the mouth of the said passages.

I do not claim, broadly, a burner or pressure-regulating device provided with opposing passages, nor do I claim a removable cylindrical 85 check-plug made to fit the inside of the burner-pillar; but

What I do claim is—

The combination, with the ordinary pillar of a gas-burner, of a pressure-regulating plug 9c made to fit inside and detachably connected with said pillar, the plug being provided with passages along the sides at one end, an axial passage leading from the other end, and opposing or centripetal passages leading from 95 the outside passages to the axial passage, said centripetal or opposing passages leading toward one another to a point where the jets of gas issuing therefrom will impinge directly against one another, substantially as described. 100

In testimony whereof I affix my signature in presence of two witnesses.

ORSON W. BENNETT.
